Filed Aug. 8, 1972, Ser. No. 278,799

Term of patent 7 years

Int. Cl. D15—01

U.S. Cl. D77—1 A

FIG. 1 is a front perspective view of a crankshaft calibrator degree wheel showing my new design;

FIG. 2 is a rear elevational view thereof;

FIG. 3 is a top plan view thereof;

FIG. 4 is a bottom plan view thereof;

FIG. 5 is a side elevational view thereof;

FIG. 6 is a front perspective view of another embodiment of my new design wherein an imperforate retaining plate has been substituted for the annular retaining ring of FIG. 1.

I claim:

The ornamental design for a crankshaft calibrator degree wheel, substantially as shown and described.
